ATTORNEY

UNITED STATES PATENT OFFICE

160,269

CONVERTIBLE FACE HOOD AND MAKE-UP
CAPE

Gladys N. Morganti, Denver, Colo.

Application January 3, 1949, Serial No. 30

Term of patent 7 years

(Cl. D3—3)

To all whom it may concern:

Be it known that I, Gladys N. Morganti, a citizen of the United States of America, residing at Denver, in the county of Denver and State of Colorado, have invented a new, original, and ornamental design for Convertible Face Hood and Make-Up Cape, of which the following is a specification, reference being had to the accompanying drawing, forming part thereof.

In the drawing:

Fig. 1 is a front view of a convertible face hood and make-up cape, showing the new design; and

Fig. 2 is a side edge view thereof.

The characteristic features of my convertible face hood and make-up cape comprise a body of the configuration shown, the sides of which converge from the bottom toward the intermediate portion and the upper side edges being gradually curved inwardly to form inverted V-shaped upper flap portions, there being a neck-encircling opening formed at the upper portion

of the body, with tie strings extending from the free edges of the neck-encircling opening, the lower edge of the body tapering from the respective lower corners to the center, with tie strings extending from the lower corners of the body and the lower central portion of the body being bowed all as shown.

I claim:

The ornamental design for a convertible face hood and make-up cape, as shown and described.

GLADYS N. MORGANTI.
